CALCULATING MACHINE

George C. Chase, South Orange, N. J., assignor
to Monroe Calculating Machine Company,
Orange, N. J., a corporation of Delaware

Original application November 27, 1935, Serial
No. 51,810. Divided and this application Jan-
uary 21, 1938, Serial No. 186,077

4 Claims. (Cl. 235—79)

The invention relates to calculating machines and more particularly to operation control devices therefor, adapted to interrupt the operation of the numeral wheel actuators, the present application having been divided from application Serial No. 5 51,810, filed November 27, 1935, and entitled Calculating machine.

The invention consists in the novel construction and combination of parts, as set forth in the 10 appended claims.

In the accompanying drawings illustrating the invention:

Fig. 1 is a right side elevation of a calculating machine embodying the invention, with the casing 15 removed.

Fig. 2 is an enlarged vertical section of the selector and registering mechanism.

Fig. 3 is a developed cross sectional view through a numeral wheel and its associated driving pinion 20 and tens transfer elements.

Fig. 4 is a side elevation of the numeral wheel and associated parts, with parts shown in section.

Fig. 5 is a plan view of certain numeral wheel locating mechanisms.

Fig. 6 is a detail face view of a portion of the variable speed drive gearing.

Fig. 7 is a left side elevation of the machine, with casing removed and with the carriage shown in section.

Figs. 8 and 9 are detailed views of parts shown in Figure 7.

The invention is shown as applied to a reversible cycle calculating machine which, in order to simplify the disclosure, is operated by means of a reversible crank handle 3. The mechanisms involved are however primarily designed for high speed operation, and it will be obvious that a machine of this kind could be equipped with a motor drive such, for instance, as that disclosed in United States Patent No. 1,566,650, issued to George C. Chase on December 22, 1925.

In the drawings, a reversible crank handle 3 (Fig. 1) has driving connection with a train of gears 4, designed to drive a shaft 5 in one-to-one ratio with said handle. Shaft 5, through one-to-one gearing connection (not shown) with shaft 8 (Fig. 7), operates certain constantly driven portions of the machine, as will later appear, and also provides an intermittent drive for the differential actuators of the machine, by means of a mechanism disclosed in United States Patent No. 1,858,763, issued to George C. Chase on May 17, 1932.

It is desired to hold the actuators inactive during the first quarter cycle of crank handle move-

ment; to give them a harmonically accelerated and diminished movement during the second and third quarters of the cycle, and to hold them at rest during the final quarter. For this purpose, an elliptic gear 33 fixed upon shaft 5, meshes with an elliptic gear 34 (Figs. 1 and 6) loosely mounted on stud 39 and having planetary gear connection with actuator gear 35 also loosely mounted on stud 39. This connection comprises a pair of fixedly connected planet pinions 36 and 37, eccentrically mounted on the elliptic gear 34, and a sun gear 38 loosely mounted on the stud 39 supporting said elliptic gear. Gear 35 meshes with pinion 37, while sun gear 38 meshes with pinion 36 and also with the teeth of segment 40, having anti-friction 10 roller engagement with a pair of cams 41, fast upon shaft 5.

Cams 41 are designed to give the desired movement to the gear 35, the elliptic gears 33 and 34 serving to cooperate in the driving of gear 35 and, by approximating the desired drive ratios, to lighten the work of the cams 41.

Gear 35 drives pinions 42 and 43, fast upon the hubs of a pair of pinion wire gears 44 and 45 (Fig. 2) extending across the machine. An idler gear 46 is interposed between gear 35 and pinion 43, to reverse the direction of rotation of the pinion wire gear 45 relative to the gear 44.

A locator cam 153 is fast with one of the gears 4, and is engaged by the anti-friction roller of a 30 locator arm 155, exerting pressure upon said cam by means of a spring 156.

The differential actuator mechanism, shown in Fig. 2, is of the type wherein different gear trains, 49, are engaged selectively with the drive gears, 35 44 or 45 under the control of settable digit keys 18 movement being transmitted, during the operation of the machine, from the gear trains 49 to the actuator output gears 80 and thence to the numeral wheels 13 of the register. This construction forms no part of the present invention, and one of a number of other well known forms of differential actuating mechanism might be employed.

The tens transfer mechanism is of the wheel to 45 wheel type disclosed in the United States patent to Chase No. 1,964,314, issued June 26, 1934. This comprises a direct gearing connection between the numeral wheels of the register, the gearing being of the entocyclic type, distinguishing from epicyclic gearing in that a floating gear is carried in an eccentric orbit within the circumference of an internal gear. Registrations according to the setting of pinions 49 are transmitted to the numeral wheel 13 through gear 80 (Fig. 2), pin- 50 55

ions 10 and 11 (Fig. 3) and the eccentrically mounted floating gear 14. The orbital gearing is so designed that for each unit of value selected by the pinions, gear 80 will transmit a four tooth 5 movement or a third of a rotation to the pinion 11 secured to the eccentric hub of floating gear 14. This floating gear has external and internal teeth, the latter engaging the teeth of a pinion 26 and the former engaging an internal gear 15, secured 10 to the numeral wheel 13. The floating gear has three more internal teeth than are provided on pinion 26, and three less external teeth than internal gear 15, so that a 120 degree eccentric movement of the floating gear 14 within the gear 15 will impart a one tooth movement to the numeral wheel in the well known manner. Geared 15 to each numeral wheel 13 is a plate 16 upon which is mounted a transfer roller 19 movable through the teeth of a star wheel 23, fast with the pinion 20 26. This will impart a direct gear movement to the floating gear 14, to register the tens transfer. Plate 16 forms a locking plate acting upon a 25 detent 27, and thereby upon the star wheel 23, to prevent overthrow of the tens transfer mechanism. Lost motion is taken out of the gear train connection between the numeral wheels, and the tens transfer is completed at the end of each cycle, by means of a series of successively acting alignor cams 29, operating upon the detents 27 30 through an intermediate member 30. These alignors are secured upon the numeral wheel supporting shaft 17, which is driven through gearing 31, 32, and 33 (Fig. 7), from through shaft 8, previously referred to.

35 The numeral wheels 13 (together with the usual revolution counting wheels 84) and the related tens transfer mechanism are mounted in a transversely shiftable carriage 2, and in order to hold the numeral wheel gearing in alignment 40 during a shifting movement of said carriage a comb 85 (Figs. 2 and 5) is provided, through the teeth of which comb the gears 10 pass as they move out of engagement with the gears 80. As the gears 10 are moved laterally beyond the base 45 of the machine, they are locked by the action of spring detents 86. The detents 86 related to the gears 10 which are in mesh with the gears 80 of the machine are held out of contact with such gears 10 by means of rollers 87 of the detents engaging a track 88 formed by the outer face of the comb 85, which is supported in the base of the 50 machine.

Operation control

United States Patent No. 1,544,806, issued to George C. Chase on July 7, 1925, shows means for interrupting operation of the machine when the registration on the numeral wheels passes from positive to negative or from negative to positive, these means being particularly useful in performing division operations, as set forth in that patent.

When the registration becomes negative, a subtractive tens transfer occurs in the numeral wheel 13 standing at the time immediately to the left 55 of the keyboard, this wheel being moved from 0 to 9 registering position. In the structure disclosed herein this results in the movement of a pin 89 secured in the alignor cam 16 from the position shown in full lines in Fig. 7, into the dotted line position. According to Patent No. 1,544,806, it is necessary, at the end of a cycle 60 during which the change has occurred, to move a trigger 31 out of engagement with the shoulder of a spring-pressed pawl 25, carried by arm 24,

normally held in rearward position by its spring 28. This allows pawl 25 to drop into the path of movement of a shoulder of rock arm 22 which arm is oscillated by means of link 21 and crank arm 20 from the constantly driven shaft 8. Arm 24, thus coupled to arm 22, will be carried forwardly against a fixed stop 32, whereby continued rotation of the machine in either given direction will be prevented. Upon reversal of movement of the crank handle, arm 24 will be allowed to move 10 rearward and pawl 25, engaging the end of trigger 31 will be lifted out of engagement with the shoulder of arm 22, freeing the machine for movement in either desired direction.

In the present structure, however, the direct 15 operation of the trigger 31 by pin 89, as shown in Patent No. 1,544,806, is unsuitable. This is true because there may be sufficient lost motion in the differential gear train to allow a forward whip of the higher order wheels sufficient to bring 20 the pin 89 into engagement with the trigger even though the wheels should not have passed from 0 to 9 or from 9 to 0 registering position.

According to the present invention, therefore, a tripping lever 90 is fulcrumed upon the end of 25 a U-shaped member 91, having pin and slot connection at 92 with the frame of the machine. Member 91 is raised, against the tension of its spring 98 immediately after the completion of each cycle of operation of the machine, by means of a lever 93 fulcrumed on the machine frame at 94, engaging member 91 through an interposed link 95, and being engaged by a tooth 96, loosely mounted on shaft 8, and engaged in turn by a pin 101 (Fig. 8) in arm 97, having pin and slot connection with the crank arm 20 of shaft 8. The pin and slot connection of the parts 20 and 97 provide for the action of tooth 96 upon lever 93 after the crank handle 3 has passed through full cycle position in either direction of rotation, while the picking up of tooth 96 by arm 97 provides lost motion upon reversal of the drive and thus prevents movement of lever 93 immediately the rotation of crank handle 3 is started.

Lifting of member 91 by lever 93 will bring the rearward end of lever 90 into the position occupied by pin 89 when the related numeral wheel stands at 9, and, upward movement of member 91 continuing and lever 90 being in contact with pin 89, a pin in the forward end of lever 90 will lift the trigger 31 and disengage pawl 25, to effect the stop.

In order that the stop may be operated when the registration in the numeral wheels 13 changes from negative to positive, as well as in the change from positive to negative, above described, means are provided for changing the position of the member 91 at the end of a cycle of additive operation, as compared with the position of said member at the end of a cycle of subtractive operation. For this purpose an anti-friction roller 102 on the member 91 engages a disc 99, eccentrically mounted on the shaft 8, and having pin and slot connection with one of the gears 83, member 91 being held against the disc under the 60 tension of a spring 100. The pin and slot connection between parts 83 and 99 is so arranged that during additive rotation of the crank handle 3 lever 90 will be carried rearwardly, into the position illustrated in Fig. 7, at the end of each 65 cycle, so that upon the action of tooth 96 on lever 93 the rear end of lever 90 will move to or across the position occupied by pin 89 when the numeral wheel 13 registers 0. On the other hand, in subtractive rotation, of crank handle 3, the pin of 70 75

5 gear 83 will be located in the opposite end of the slot of disc 89, so that at the end of a cycle of the crank handle the rear end of lever 90 will be under the pin 88 when numeral wheel is in 9 registering position, and the action of tooth 96 will cause the tripping of trigger 31 if the pin 88 is in such position.

10 Means are shown for setting the automatic stopping mechanism from active to inactive position, this means comprising the lever 303, to which the link 95 is pivoted, said lever being settable in a clockwise direction as viewed in Fig. 7 to bring a reduced portion of the link 95 between the lever 83 and the cooperating portion of member 91. This will allow movement of lever 93, under the influence of tooth 96, without causing a lifting movement of member 91. Lever 303 is retained in either of its set positions by a spring 15 click 307.

20 United States Patent No. 1,566,650, above referred to, shows how this stopping mechanism may be used in a motor driven machine, while United States Patent No. 1,888,161, issued to George C. Chase on November 15, 1932, shows how it may be employed in a full automatic division machine for giving automatic reversal of the drive, together with automatic shifting of the carriage 2 at the proper time. This latter patent also shows means for automatically setting lever 303 into active position when the automatic division lever is moved to begin an operation, and for automatically restoring lever 303 at the end of the division operation, parts 303 and 307 being similarly numbered in that patent.

25 35 United States Patent No. 1,964,211 issued to Austin A. Overbury on June 26, 1934, shows how the above described stop mechanism may be employed to secure full automatic multiplication.

I claim:

40 1. In a calculating machine having registering units including each a numeral wheel and a gear provided with a projection, cyclic differential actuators for said wheels, and drive means for said actuators; automatic stopping means for said drive means, control means normally operable at the end of each actuator cycle to feel the position of one of said register unit projections and 45 cooperating therewith upon contact to render the

stopping means active, means for adjusting said control means to contact the projection at one or alternatively at the other of two given radial positions thereof, and means adjustable to render the control means active or inactive.

5 2. In a calculating machine having a register provided with elements positioned in accordance with the value registered, cyclic differential actuators for said register, means for driving said actuators, and means for selectively determining 10 additive or subtractive registration; automatic stopping means for said driving means, and a control device for said stopping means variably operable according to the determined sign of registration and including elements adapted to cooperate with the register elements in one or alternatively in another value indicating position thereof.

3. In a calculating machine having registering means including each a numeral wheel and a gear provided with a projection, cyclic differential actuators for said wheels, and drive means for said actuators; automatic stopping means for said drive means, and a control device including an element reciprocated at the end of each actuator cycle in a path intersecting the path of movement of a register unit projection and cooperating with said projection, when the related wheel rests in 9 registering position, to render the stopping means active.

4. In a calculating machine having registering means including each a numeral wheel and a gear provided with a projection, cyclic differential actuators for said wheels, means for driving said actuators, and means for selectively determining additive or subtractive registration; automatic stopping means for said driving means, and a control device including an element reciprocated at the end of each actuator cycle in a path intersecting the path of movement of a register unit projection and cooperating with the projection to render the stopping means active, and an element operable variably in additive and in subtractive registration to guide the reciprocating element into contact with the register unit projection when the related wheel rests in 0 or in 9 registering position, respectively.

GEORGE C. CHASE.
